INSULATING HOLDER FOR BEVERAGE POTS

Rena Bell Hardman, 10401 Wilshire Blvd.,
West Los Angeles, Calif.

Filed Mar. 25, 1963, Ser. No. 74,120

Term of patent 14 years

(Cl. D92—26)

Fig. 1

Fig. 2

Fig. 3

Fig. 4

FIGURE 1 is a perspective view of an insulating holder for beverage pots, showing my new design, with a front portion of a teapot shown in broken lines for illustrative purposes only;

FIGURE 2 is a side elevational view thereof;

FIGURE 3 is an end elevational view; and

FIGURE 4 is a bottom plan view of the same.

I claim:

The ornamental design for an insulating holder for beverage pots, substantially as shown and described.
